TREATMENT OF HYDROCARBONS

Gustav Egloff, Chicago, Ill., assignor to Universal
Oil Products Company, Chicago, Ill., a corpora-
tion of Delaware

Application June 7, 1940, Serial No. 339,291

2 Claims. (Cl. 196—52)

This invention relates to the treatment of hydrocarbon oils to produce large yields of high antiknock gasoline. More specifically, it is directed to the cracking treatment of hydrocarbon oil by catalytic and thermal means where the oil and conversion products therefrom are selectively utilized in the production of large yields of said high antiknock gasoline.

In one specific embodiment the present invention comprises admixing a powdered cracking catalyst with a relatively heavy hydrocarbon oil which may be vaporized without substantial decomposition, together with reflux condensate of a similar boiling point range and formed as hereinafter described, and heating the admixture under adequate conditions of time, temperature and pressure to produce substantial yields of high antiknock gasoline in the presence of a hydrogen-containing gas from the process and similarly admixing a reforming catalyst powder with a relatively light hydrocarbon oil containing also insufficiently converted hydrocarbons of similar boiling point range and formed as hereinafter described, heating the admixture under adequate conditions of time, temperature and pressure to produce high antiknock gasoline in the presence of relatively saturated gases from the process, directing these reaction products to a reaction chamber together with other hydrocarbons undergoing thermal cracking treatment as herein-after described, separating the products of the mixed reactions into a non-vaporous liquid residue and vaporous products, removing the non-vaporous residue as a product of the process and fractionating the vaporous products to separate gasoline and gaseous hydrocarbons from insufficiently converted hydrocarbons, condensing and separating the insufficiently converted products into a relatively heavy fraction for thermal treatment as will be hereinafter described, also an intermediate and a light reflux condensate for separately admixing with hydrocarbon oil fractions directed to catalytic cracking treatment as hereinabove described, introducing to the process a heavy oil for thermal cracking in combination with said heavy reflux condensate and directing the products from thermal cracking treatment into the catalytically converted products flowing to said reaction chamber, stabilizing the gasoline and gas from said treatments and producing stabilized gasoline of high antiknock value, a fraction relatively rich in C₃ and C₄ hydrocarbons and a hydrogen-containing gas which is subjected in part to further treatment with intermediate boiling hydrocarbons as hereinbefore described, sub-

jecting said gases rich in C₃ and C₄ hydrocarbons to polymerizing treatment to form additional yields of high antiknock gasoline and subjecting the residual gases therefrom in part to further treatment in combination with a relatively light hydrocarbon oil as hereinabove described.

According to the present invention relatively clean hydrocarbon oils which may be vaporized without substantial decomposition with insufficiently converted products therefrom constituting a relatively light and a relatively heavy fraction are separately subjected to selective catalytic cracking treatment in the presence of catalyst powder whereas heavy hydrocarbon fractions such as hydrocarbon oils having a higher tendency to deposit carbonaceous material and insufficiently converted hydrocarbons therefrom are subjected to thermal cracking treatment. As a net result, a wide range of hydrocarbon oils are utilized as charging stock under selective conditions suitable for producing maximum yields of high antiknock gasoline. Highly branched chain hydrocarbons are produced as a result of the catalytic cracking treatment and the introduction of saturated gases from the process and hydrogen-containing gases into the fractions undergoing selective cracking and reforming treatment increases the degree of saturation of the products and reduces the rate of carbon deposition upon the catalyst. As a result of mixing the thermally and catalytically cracked reaction products, hydrogen transfer reaction are favored which also function to saturate the gasoline product. Other features of the invention will become apparent in connection with the description of the flow and specific features involved in the attached diagrammatic drawing.

The catalyst powder employed particularly in catalytic cracking reactions may be from a naturally occurring material or may be an artificial catalyst of a more or less porous and refractory nature such as the type consisting essentially of siliceous and aluminous material. The particular catalytic material employed will depend in some measure upon the extent of the catalytic cracking of the oil, the manner of handling the spent catalyst and the character of the gasoline product. Untreated or acid-treated clays, kieselguhr or fuller's earth in some cases with added difficultly reducible oxides, are suitable, likewise synthetically composited catalysts such as hydrated silica and hydrated alumina concurrently or separately precipitated and preferably washed free from detrimental adsorbed impurities. Special methods may be employed

whereby a finely divided powder of low density is obtained. Generally speaking, the primary and major component is a precipitated hydrated silica which is usually admixed with a precipitated hydrous metal oxide such as alumina, zirconia, or mixtures thereof, and present in minor proportions. According to one general method of preparation, the hydrated silica may be precipitated from a dilute solution of a commercial water-glass under carefully regulated conditions and subsequently admixed with the remaining hydrous oxide components. The hydrated silica may be admixed with the hydrous oxide components in any suitable manner, as for example, by suspending the precipitated hydrated silica in a solution of a metal salt and precipitating the corresponding hydrous oxide in the presence of the suspended hydrated silica by the addition of a suitable alkaline precipitant. Various other procedures may be followed wherein these components may be co-precipitated or separately precipitated, and the components intimately admixed whether one or more hydrous oxides are composited with the hydrated silica. Added hydrous oxides may be simultaneously or consecutively deposited. The hydrated silica may also be heated in solutions of metal salts and hydrous oxides deposited in the presence of hydrated silica by hydrolysis, or the precipitated hydrated silica may be admixed with a relatively concentrated solution of a metal salt to form a paste and then heated to deposit the desired metal oxides. Where alkali metal impurities such as sodium compounds have been adsorbed into the catalytic material during preparation, it may be desirable to treat the material at some state of its preparation in order to remove alkali metal impurities. This may be accomplished by washing with various acidic and salt solutions before or after drying in the event that the catalyst is dried, or prior to compositing the hydrated silica with the remaining hydrous oxides. The finished catalytic masses of the preferred synthetic type contain in addition to the hydrated silica, alumina and/or zirconia in amounts varying over a relatively wide range, particularly good results having been obtained when using 5 to 30 weight per cent of added alumina and/or zirconia.

While the above described silica-alumina type catalysts are particularly useful in catalytic cracking reactions, they may also be employed in the reforming reactions carried out in the present process. Other reforming catalysts may also be utilized, however, such as activated alumina supporting oxides of the elements in the left-hand column of groups IV, V and VI of the periodic table. In these catalysts the alumina constitutes the major component whereas the remaining components are present in minor proportions. Various other oxides have been utilized as the major component such as zinc oxide, titanium oxide and various others but good results are obtained when utilizing activated alumina which is substantially in the gamma form. Although the activated gamma form of alumina may be used in the preparation of the catalyst, it is also possible to utilize aluminum hydroxide or aluminum hydrate which may be subsequently dehydrated and activated at a temperature of approximately 1200° F. The added oxide is preferably an oxide of chromium which when properly prepared is in the sesqui-oxide form. When preparing the catalyst, a solution of chromium trioxide is usually added to the activated

alumina preferably while in a fine state of division and is subsequently dried and calcined at a temperature of approximately 850-1200° F. From 5 to 35% or more of chromium sesquioxide, based on the activated alumina, is effective in this form of catalyst. Various other oxides may be added to the alumina-chromia during preparation such as soluble magnesium and zinc compounds which upon subsequent calcination yield minor amounts of oxides of these elements which serve to stabilize the activity of the alumina-chromia catalyst. Thus, a catalyst may be prepared which consists of approximately 86% of alumina, 12% chromia and 2% of zinc oxide which in the powdered form is highly suitable for use in the reforming reactions subsequently described.

The accompanying drawing illustrates diagrammatically in conventional side elevation one specific form of apparatus which may be used to accomplish the objects of the invention. It is not drawn to any exact or relative scale and serves only as an illustration of the scope of the basic features constituting the invention.

Referring to the drawing, a relatively heavy hydrocarbon oil which may be vaporized without substantial decomposition and containing a suspension of cracking catalyst powder is admitted to the process through line 1 and valve 2 leading to pump 3 which pumps this oil through line 4 and valve 5 into line 6 where it is admixed with insufficiently converted hydrocarbons having a similar boiling range and hydrogen-containing gas produced in the process and introduced from the absorber column by line 96 and then directed to the heating element 7 heated in furnace 8. Temperatures employed will be within the approximate range of 700 to 1100° F. and the pressure may range from approximately atmospheric to 1000 pounds per square inch. Products leaving the heating element 7 which may have been more or less completely reacted in the presence of suspended catalyst are removed through line 9 regulated by valve 10 and directed to the separating drum 11 wherein non-vaporized oil containing more or less spent catalyst is separated from vaporous reaction products, the non-vaporous fraction being withdrawn through line 11' regulated by valve 12 and the vaporous products flowing through line 13 and valve 14 into line 15 where these products are mixed with other cracked products flowing to reaction chamber 16.

Similarly, a relatively light hydrocarbon charging stock such as naphtha for example, and containing in suspension a reforming catalyst powder, is admitted to the process through line 17 containing valve 18 leading to pump 19 which pumps this oil through line 20 containing valve 22 and into line 23 where it may be admixed with insufficiently converted products produced in the process as hereinafter described and then directed to heating element 24 heated in furnace 25. Temperatures and pressures will usually be somewhat higher than those above described for catalytic cracking and will be substantially within the same range. Heated and catalytically reformed products leaving the heating element 24 which may have been more or less completely reacted in the presence of said suspended catalyst are removed through line 26 regulated by valve 27 and directed to the separating drum 28 where a non-vaporized oil containing more or less spent catalyst is separated from vaporous products, the non-vaporous fraction being withdrawn through line 29 regu-

lated by valve 30 and the vaporous products flowing through line 31 and valve 32 and then into line 15 leading into said reactor 16. A relatively heavy hydrocarbon oil as compared with the said oils introduced into the process through lines 1 and 17 is admitted to the process through line 33 containing valve 34 leading to pump 35 which pumps this oil through line 36 and valve 37 for mixing with a heavy reflux condensate separated in fractionating column 48 as will be hereinafter described admitted through line 63 and is then directed to heating element 38 heated in furnace 39. This hydrocarbon oil is thermally cracked under thermal cracking conditions of approximately 850-1000° F. and approximately 100 to 500 pounds per square inch pressure. The products leaving heating element 38 are directed through line 15 regulated by valve 40 into said reaction chamber 16 for admixture with said catalytically treated products undergoing reaction. Products from thermal and catalytic cracking are removed from reactor 16 through line 41 regulated by valve 42 and are directed to the separating chamber 43 where non-vaporous residue is separated from vaporous products. The non-vaporous residue is removed from separating chamber 43 through line 44 regulated by valve 45 and vaporous products are removed through line 46 containing valve 47 and directed into the fractionating and separating column 48 where insufficiently converted products are separated from gasoline-containing products. Hydrocarbons of gasoline boiling point range are removed overhead together with gaseous hydrocarbons through line 49 containing valve 50 and flow through condenser 51 where they are cooled and condensed, and thence directed through line 52 containing valve 53 to receiver 54 where the gasoline product is separated from normally gaseous hydrocarbons. A portion of the gasoline product in receiver 54 is removed through line 55 containing valve 56 and directed to pump 57 which pumps this oil through line 58 and regulated by valve 59 into the top of fractionating and separating column to assist in controlling the character of the overhead product. Insufficiently converted products in fractionating and separating column 48 are separated into a relatively heavy high boiling reflux condensate, an intermediate boiling and a relatively light boiling reflux condensate. Said heavy reflux condensate is withdrawn from the bottom of the column 48 through line 60 containing valve 61 leading to pump 62 which pumps this oil through line 63 and valve 64 into line 36 where it is admixed with heavy oil directed to the process for thermal cracking treatment as hereinabove described. Insufficiently converted hydrocarbons of intermediate boiling point range are removed from column 48 through line 65 containing valve 66 leading to pump 67 which pumps this oil through line 6 containing valve 68 where it is admixed with relatively heavy oil which will not undergo substantial decomposition under vaporization introduced through line 4 and hydrogen-containing gases introduced through line 96 whereupon the mixture undergoes catalytic cracking treatment as hereinabove described. Insufficiently converted hydrocarbons of relatively light boiling point range are removed from fractionating column 48 through line 69 containing valve 70 leading to pump 71 which pumps this oil through line 23 containing valve 72 where this oil is admixed with relatively light hydrocarbon oil charged to the process through line 28 and

paraffinic gases admitted through line 130 which are then catalytically cracked as hereinabove described.

Unstabilized gasoline removed from receiver 54 is removed through line 21 regulated by valve 13 leading to pump 74 which pumps this oil through line 15 and valve 16 into the stabilizing column 11. The oil is heated in the bottom of stabilizing column to effect partial vaporization thereof by indirect heat exchange with the heat exchanger 18 which may be supplied with heat from an oil at suitable temperature from the process or by steam. The stabilizer is preferably operated so that gases rich in C₃ and C₄ hydrocarbons are removed from the stabilized gasoline, the top temperature being controlled by passing a cooling medium through the cooling coil 19. The stabilized gasoline is removed from the bottom of stabilizing column 11 through line 132 regulated by valve 133 and gases rich in C₃ and C₄ hydrocarbons flow from the top of stabilizer through line 80 and valve 81 leading to the heating element 113 and thence to the polymerizing chamber 82 for polymerizing treatment as will be subsequently described. Gaseous hydrocarbons which may be rich in C₃, C₄, and even C₅ hydrocarbons are removed from the receiver 54 through line 83 regulated by valve 84 leading to the compressor 85 which compresses these gases and directs them through line 86 and valve 87 to the absorbing column 88 where the gases rich in C₃ and higher hydrocarbons are preferably removed from said gases. A hydrocarbon oil from an external source or a product of the process may be utilized as an absorber oil and admitted to the absorbing column 88 through line 89 and valve 90. This oil flows countercurrent to the ascending hydrocarbons thereby absorbing C₃ and higher hydrocarbons. Hydrogen-containing gases consisting largely of hydrogen admixed with methane and C₂ hydrocarbons are removed from the absorbing column 88 through line 91 containing valve 92 and may be removed in part from the process through line 93 regulated by valve 94 and the remainder directed to the compressor 95 which compresses this gas and directs it through line 96 containing valve 97 into the oil being directed to heating element 1 for catalytic cracking treatment as hereinabove described. Enriched absorber oil is removed from the bottom of column 88 through line 98 and valve 99 leading to pump 100 which pumps this oil through line 101 and valve 102 into the stripping column 103. Heat is supplied to the absorber oil at the bottom of stripping column 103 through heat exchanger 104 which is supplied with heat by means of heated oil from the process or steam, and cooling at the top of the stripping column is carried out by means of cooling coil 105. The column is preferably operated so that gases rich in C₃ and C₄ hydrocarbons are removed overhead and the absorber oil removed contains C₅ or higher hydrocarbons removed from the gases. The partly stripped absorber oil is removed through line 106 regulated by valve 107 and may be directed to suitable conventional means for removing C₅ hydrocarbons for blending with the gasoline product for example, and either returning the absorber oil to the absorbing column for further use or directing to the process for cracking treatment. The gases rich in C₃ and C₄ hydrocarbons are removed at the top of the stripping column 103 through line 108 containing valve 109 and admixed with similar gaseous hydrocarbons removed from the stabilizing column 11 and flowing through line 80 as previously described.

These gases are directed to the compressor 110 which compresses and directs them through line 111 and valve 112 to heating element 113 and located in furnace 114 where the hydrocarbons are heated under pressure to a temperature suitable for polymerization reactions and are then directed through line 115 containing valve 116 to the polymerizing chamber 82. The polymerizing reaction may be carried out in any desired manner, the preferred method, however, being in the presence of a phosphoric acid catalyst consisting essentially of orthophosphoric acid disposed upon a siliceous adsorbent. The temperatures employed when using supported phosphoric acid catalyst may be within the range of 200 to 650° F. and pressures employed may range from 100-1000 pounds or more per square inch. Polymerized products are removed from the polymerizing chamber 82 through line 117 regulated by valve 118 and directed to a cooler and condenser 119 and the cooled and condensed products then flow through line 120 containing valve 121 to a separating drum 122 where the polymer gasoline is separated from substantially paraffinic gases. The polymer gasoline is removed from the separating drum 122 through line 123 regulated by valve 124 and the paraffinic gases are removed through line 125 containing valve 126 and may be removed in part through line 127 regulated by valve 128, the remainder being directed to a compressor 129 which compresses these gases and directs the compressed gas through line 130 and valve 131 into the hydrocarbon oil flowing through line 23 for conversion treatment in heating element 24 as hereinabove described.

An example of one specific operation of the process as it may be accomplished in an apparatus such as illustrated and above described is approximately as follows: A distillate fraction from Mid-Continent crude oil corresponding approximately to a heavy gas oil cut containing in admixture therewith insufficiently converted hydrocarbons of similar boiling point range produced in the process as hereinafter described and having added thereto also a hydrogen-containing gas produced in the process, is admixed with approximately 1% by weight of a synthetic silica-alumina catalyst powder prepared according to procedures above described. It is then heated to a temperature of approximately 900° F. at a pressure of approximately 100 pounds per square inch and is passed to a separating drum where substantially spent catalyst is removed as a suspension in a non-vaporous oil and the vaporous products are directed into a reaction vessel and commingled with other fractions undergoing cracking treatment as hereinafter described. Similarly, a distillate fraction corresponding to a heavy naphtha cut having admixed therewith insufficiently converted hydrocarbons of similar boiling point range produced in the process as hereinafter described and having also added thereto paraffinic gases remaining after polymerization treatment of C₃ and C₄ hydrocarbons resulting from the process, is admixed with approximately 2% by weight of an alumina-chromia powder prepared by depositing approximately 8% chromia upon activated alumina. It is then heated at a temperature of approximately 975° F. under a pressure of approximately 500 pounds per square inch and directed into a separating drum wherein a small amount of non-vaporous residue containing relatively spent catalyst powder is separated and withdrawn while the vaporous reaction products

are directed to said reaction vessel and commingled with hydrocarbons undergoing reaction as hereinbefore and hereinafter described. Reduced Mid-Continent crude oil in admixture with heavy reflux condensate resulting from the fractionation of the insufficiently converted products from the process are heated under thermal decomposition conditions of approximately 875° F. at a pressure of approximately 175 pounds per square inch and the reaction products are commingled with the reaction products from catalytic cracking and directed to the reaction vessel. The reaction products from thermal and catalytic cracking are directed to a separating chamber from which the liquid residue is withdrawn which is a fuel oil grade and corresponds to approximately 15% based on the total oil charged to the process. The spent silica-alumina and alumina-chromia powders suspended in non-vaporous hydrocarbon oil from the respective steps of the process may be separately directed to flashing for other treatment whereby spent catalyst powder is separated from contained hydrocarbon oils, said separated hydrocarbon oils being further converted in the succeeding steps described while the catalysts are regenerated by solvent and/or oxidation treatment to remove hydrocarbonaceous deposits whereupon the regenerated catalyst powders are returned to the respective steps in admixture with fresh catalyst. Vaporous products are directed to the fractionating system where insufficiently converted products are separated and subjected to further conversion treatment as hereinabove described while the gasoline and gaseous products are removed overhead and cooled, condensed and separated. The unstabilized gasoline and gases are subjected to stabilization treatment in conventional equipment whereby a stabilized gasoline is formed and two gaseous fractions, one rich in C₃ and C₄ hydrocarbons and the other consisting essentially of hydrogen, methane and C₂ hydrocarbons. The C₃ and C₄ hydrocarbons are subjected to polymerizing treatment in the presence of a solid phosphoric acid catalyst at a temperature of approximately 475° F. using a pressure of approximately 400 pounds per square inch. The polymer gasoline therefrom is admixed with the gasoline product from the process while the residual paraffinic gases are admixed with the relatively light hydrocarbons directed to conversion treatment in the presence of alumina-chromia catalyst powder as hereinabove described. Said hydrogen-containing gas separated from C₃ and C₄ hydrocarbons is admixed in part with the hydrocarbons substantially of gas oil boiling point range admitted to the process in admixture with insufficiently converted hydrocarbons and containing silica-alumina catalyst powder as hereinabove described. This operation will yield approximately 76% of 76 octane number gasoline based on the total oil charged to the process, non-vaporous residue being separated in the amount noted while the balance is attributed mainly to normally gaseous products, only a relatively small percentage appearing as hydrocarbonaceous deposits upon the catalyst powders.

I claim as my invention:

70 1. A process for the conversion of hydrocarbon oil which comprises catalytically reforming a relatively light oil, catalytically cracking a heavier oil and thermally cracking a residual oil, combining resultant conversion products, separating residue from vapors, fractionating said vapors to

separate and condense light, intermediate and heavy reflux condensate from the fractionated vapors, supplying said light reflux condensate to the catalytic reforming step, supplying said intermediate reflux condensate to the catalytic cracking step, supplying said heavy reflux condensate to the thermal cracking step, cooling and condensing said fractionated vapors, separating distillate from gases, separating said gases into at least two fractions, a light gas fraction comprising ethane and lighter gases and a heavy gas fraction comprising propene and heavier nor-

mally gaseous hydrocarbons, subjecting said heavy gas fraction to polymerization, supplying unpolymerized gases to the catalytic reforming step and at least a portion of said light gas fraction to the catalytic cracking step.

2. The process of claim 1 further characterized in that catalytic reforming is accomplished in the presence of a powdered dehydrogenation catalyst and catalytic cracking in the presence of a powdered cracking catalyst.

GUSTAV EGLOFF.
